UNITED STATES PATENT OFFICE.

ABRAHAM WEISS, OF NEW YORK, N. Y.

ATTACHMENT FOR MOTOR VEHICLES.

Application filed November 9, 1923. Serial No. 673,795.

To all whom it may concern:

Be it known that I, ABRAHAM WEISS, a citizen of the United States, residing at New York, in the county of New York and State of New York, have invented certain new and useful Improvements in Attachments for Motor Vehicles, of which the following is a specification.

This application is a continuation in part of the one filed January 23, 1923, Serial No. 614,363. The invention relates to motor vehicles, particularly taximeter vehicles. Frequently when the vehicle stops in heavy traffic, while unoccupied, a prospective passenger runs up to the vehicle and in an attempt to enter the same either to steal a ride or because of being in a hurry, opens the door without first notifying the driver. If, at the moment when the door is open, the vehicle is set in motion, an accident may result to the prospective passenger. Accidents to the passenger or damage to the car also often result, when the door opens, while the vehicle is in motion.

The object of the invention is to prevent such accidents or damages, which I accomplish, according to the present invention, by electrical means so arranged between the door of the vehicle, the motor and the "flag" or handle of the taximeter, that when the door is opened, while the "flag" is up, when the vehicle is not occupied, the motor will fail to start, or will stop when the door opens, while the vehicle is in motion.

My invention has also other objects in view, which will appear from the detailed description thereof.

In the accompanying drawing in which similar reference characters denote corresponding parts, Fig. 1 is a side view of a vehicle partly in section showing my new device; and Fig. 2 is an enlarged cross section of a part of the vehicle and taximeter showing details of the electric means.

10 denotes a taximeter vehicle of usual construction, employing, for instance, a high tension magneto 11 to produce ignition. 12 denotes the usual "flag" controlled fare register or clock and 13 denotes a door leading into the passenger compartment. 16 denotes a switch adapted to be controlled from the "flag" or handle 12'. The contact members 16', 16² of the "flag" switch 16 are so arranged that normally, that is, when the "flag" is up or in a position indicating "vacant", the contact members 16', 16² are

closed, as shown in Fig. 2. 17 denotes the wall of the vehicle to which the door is hinged, as at 18. Between the opposite edges of the door 13 and of said wall 17, I provide a switch, which, according to the present embodiment, is constructed as follows:

In a groove 19 provided in the wall and open at its outer end, is mounted a cylindrical casing 20 of insulating material, the outer open end of which is closed by an annular member 21 of conductive material. Slidably mounted in the cylinder 20, is a disc 22 of conductive material, which is actuated by a spring 23 one end of which is fixed to the inner face of said disc 22 and the other end to a pin 24 of conductive material projecting through a perforation in the inner end wall of the cylinder. The outer face of said disc 22 has screwed or otherwise fixed to it, a plug or pin 25 of non-conductive material, which projects through and is guided in the annular member 21.

The spring 23 tends, when the door is open, to force the pin 25 outwardly and hold the disc 22 in contact with the inner face of the member 21. When the door is closed, its edge 13' will depress the plug 25 and as a result thereof, move the disc 22 out of contact with the member 21. The pin 24 forms one of the terminals of the switch and is connected to the ground by wire 26. The member 21 is connected by a wire 27 to one of the contact members, as 16', of the "flag" switch 16, and the second contact member 16² of said switch is connected by wire 28 to the magneto 11.

It will be clear that when the door of the vehicle is opened, while the latter is unoccupied, as indicated by the switch in "vacant" position, the door switch will close, the disc 22 being forced outwardly into contact with member 21. As a result, the ignition circuit will become grounded and the motor fail to start. Thereby the driver's attention will be drawn to the door and only on lowering the "flag" or closing the door, could he again open the circuit.

In case of a vehicle not using a taximeter, the switch in the door may be directly connected to the motor or its ignition system. In that case, whenever the door is opened, the ignition system will be grounded, so that the vehicle will fail to move.

It is understood that the same results

hereinbefore stated may be obtained by other means than those described and instead of the ignition system, the gas or feed may be brought under the influence of a 5 suitable means controlled by the manipulation of the door. I, therefore, do not wish to restrict myself to the details described and shown.

What I claim is:—

- 10 1. In a motor vehicle having a register with a manual control, the combination with a door, of means controlled through said door and intervening between the motor and said manual control of the register, whereby 15 the motor will be rendered ineffective, when the door is open, while the manual control is in inoperative position.

2. In a motor vehicle having a "flag" controlled fare register, a door and an electrically controlled gas ignition system, of a 20 switch controlled through said door, a switch controlled through said "flag" and electric connection between said switches and the ignition system, such that when the door is open, while the "flag" is in 25 "vacant" position, the ignition system will be ineffective.

In testimony whereof I affix my signature in presence of two witnesses.

ABRAHAM WEISS.
